UNITED STATES PATENT OFFICE

1,932,508

VEGETABLE CUTTER

Meade J. Brown, Greenville, Mich.

Application April 4, 1932. Serial No. 602,961

1 Claim. (Cl. 146—168)

The object of the invention is to provide a means by which potatoes may be easily and quickly cut lengthwise into square strips particularly suited for cooking in the style known as 5 French fried.

One form of the invention, hereinafter referred to as the cutter, is shown in the accompanying illustration in which Fig. 1 is a plan view of the cutter; Fig. 2 a side view with a part 10 of one of the sides removed; and Fig. 3 a cross section at the bevelled end of cutter bed piece showing face of follower guard, hereinafter referred to as the guard, in its extreme forward position with slotted end of guard bed piece en- 15 gaging short knives.

The invention consists of a bed piece 1, Fig. 1, on one end of which a handle is formed as shown, and the upper margin of the opposite end is bevelled as shown in Fig. 3. To bed piece 20 1 the sides 2, 2, extending beyond bevelled end of bed piece 1, as shown in Fig. 2, are attached. To the sides 2, 2 a plate 3 is attached so that one edge of said plate 3 slightly overlaps the bevelled end of bed piece 1. The under side of this over- 25lapping edge of plate 3 is bevelled to a chisel edge, hereinafter referred to as the transverse cutting edge. Short, narrow knives 4, 4, Figs. 1 and 3, are attached to the bevelled end of bed piece 1; said knives extending to plate 3 to which they are securely fastened at points close 30 to the edge of bevel on edge of said plate 3.

The guard, assembled of metal strip 5, cross bar 6, metal holder 7, and bed piece 8, is shown in Figs. 1, 2, 3. The bed piece 8, of a width allowing it to move freely forward and back on cutter bed piece 1 between sides 2, 2 and of a thickness which will just permit the free passage of its end under edge of plate 3, is slotted on one end as shown in Figs. 1, 3 so that said slotted end will engage knives 4, 4 when guard is at forward end of its travel. Cross bar 6 is attached to bed piece 8 at a point which will permit slotted end of bed piece 8 to engage knives 4, 4 when cross bar 6 reaches edge of plate 3. 45 Metal strip 5 is attached to cross bar 6 and bent into the form shown in Fig. 3, thus holding guard on bed of cutter while allowing its free movement forward and back and ready removal from cutter body by moving guard backward to end of 50 handle. A thin piece of metal 7, corrugated or smooth, is placed in the edge of cross bar 6 in a position to clear plate 3 when guard is in extreme forward position.

In operation the potato is placed lengthwise 55 on the bed piece 1 of the cutter with one end

against the transverse cutting edge of plate 3. The guard is pushed against the other end of potato, the metal piece 7 entering end of potato slightly and holding it in position. Pressure against guard will move the potato forward 60 against transverse cutting edge of plate 3 which will cut a slice from the potato, the unsliced portion passing on to plate 3. When the slice, passing under plate 3, reaches knives 4, 4 it will be cut by them into square strips.

It will be noted that the bevelled end of bed piece 1, which lies under the bevelled transverse cutting edge of plate 3, allows the slice to be 65 readily deflected away from plate 3, thus reducing friction and contributing materially to the ease of operation; and that the slotted end of guard bed piece 8, when guard is in its extreme forward position, will engage knives 4, 4, thus forcing the strips clear of knives and preventing any wedging of strips between knives. It will be 70 further noted that the guard as shown protects the hand of the operator, permits the easy application of the proper amount of force through the palm of the hand, prevents the slipping of the vegetable being cut, and is readily detachable from the body of the cutter.

I claim:

A vegetable cutter comprising a bed piece having a bevelled end and longitudinally extended sides to which is attached a plate with a bevelled cutting edge presented toward said bed piece above the bevelled end of which it projects somewhat, a series of fixed knives arranged beneath at right angles to the plate, one end of each of said knives being fastened to the bed piece and the opposite end fastened to the plate, so arranged that the plane of their cutting edges meet the plate back of the bevel of said plate, and a freely removable guard comprising a bed piece with a slotted end slidable between the side pieces and adapted to pass under the transverse cutting edge and engage the vertical knives, a cross bar to which said bed piece is attached, said cross bar bearing on side pieces of cutter, a metal strip adapted to hold said cross bar in position and 85 permitting free reciprocation.
